(57) **CLAIM**

The ornamental design for a body panel for an agricultural vehicle, as shown and described.

DESCRIPTION

FIG. 1 is a front, side perspective view of a body panel for an agricultural vehicle showing our new design;

FIG. 2 is a perspective view from the rear and the same side to that of FIG. 1 of the body panel of FIG. 1;

FIG. 3 is a side elevational view of the body panel of FIG. 1;

FIG. 4 is a front end elevational view of the body panel of FIG. 1;

FIG. 5 is a rear end elevational view of the body panel of FIG. 1;

FIG. 6 is a top plan view of the body panel of FIG. 1; and, FIG. 7 is an underneath plan view of the body panel of FIG. 1.

The design relates to a body panel for an agricultural vehicle, for example, a baler for bailing material, such as agricultural crop material. The body panel comprises a major side panel with narrow front, rear, top and bottom panels extending from the major side panel. The major side panel is slightly curved outwardly when viewed from the front and from the top, and includes an inwardly recessed panel extending over the upward portion of the major side panel.
